[57] CLAIM

The ornamental design for a stanchion for exterior luminaire, as shown and described.

DESCRIPTION

FIG. 1 is a rear perspective view of a stanchion for exterior luminaire showing our new design;

FIG. 2 is a side elevational view thereof on an enlarged scale, the opposite side being a mirror image;

FIG. 3 is a front elevational view thereof on an enlarged scale;

FIG. 4 is a bottom plan view thereof on an enlarged scale.

The luminaire is shown in broken lines for illustrative purposes only.
